UNITED STATES PATENT OFFICE

167,079

LEVELING SUPPORT FOR CARPENTER'S LEVEL

William L. Heffern, St. Petersburg, Fla.

Application January 18, 1952, Serial No. 18,110

Term of patent 14 years

(Cl. D52—1)

To all whom it may concern:

Be it known that I, William L. Heffern, a citizen of the United States of America and a resident of the city of St. Petersburg, State of Florida, have invented a new, original, and ornamental Design for Leveling Support for Carpenter's Level, of which the following is a specification, reference being had to the accompanying drawing, forming part thereof, wherein:

Fig. 1 is a side elevational view of a leveling support for carpenter's level showing my new design;

Fig. 2 is a top plan view thereof; and

Fig. 3 is an end view thereof.

The characteristic features of my design reside in the portions shown in solid lines.

I claim:

The ornamental design for a leveling support for carpenter's level, substantially as shown and described.

WILLIAM L. HEFFERN.
